CONSTRUCTION OF STOVES

Filed Dec. 1, 1927

INVENTOR
G. S. MORLEY
BY J. H. G. COOK
ATTORNEY

UNITED STATES PATENT OFFICE

GUILFORD S. MORLEY, OF UNIVERSITY CITY, MISSOURI, ASSIGNOR TO MAJESTIC MANUFACTURING COMPANY, OF ST. LOUIS, MISSOURI, A CORPORATION OF MISSOURI

CONSTRUCTION OF STOVES

Application filed December 1, 1927. Serial No. 236,894.

This invention relates generally to stoves and similar heating devices and particularly to a construction for devices of this character which will permit the separate elements of 5 which one of the devices is comprised to be assembled, to produce a unitary construction, without the use of bolts or other fastening devices.

Prior to this invention the separable parts, 10 notably the front, rear, and side walls, of a rectangular stove of the range type were ordinarily secured together by bolts or other similar fastening devices. These fastening devices were objectionable for several reasons 15 but principally because of the exposed head portions thereof detracted from the outward appearance of the stove. An important object of the present invention therefore is to so construct the separable elements of a stove 20 that they may be secured together without the aid of bolts or other similar fastening devices whereby the objection recited above is eliminated.

Another object of the invention is to provide unique means whereby decorative elements may be attached to a stove in such a manner that no fastening devices for securing said elements to the stove are visible at the outside of the stove whereby the decorative 25 properties of said decorative elements are enhanced.

Other features and objects of the invention will become apparent from a reading of the following specification in the light of the 30 accompanying drawings, in which,

Fig. 1 is a perspective of a stove of the range type, made in accordance with the invention, the top portion of said stove being removed to illustrate the manner in which the front, rear and side walls thereof are attached together.

Fig. 2 is an enlarged elevation of a fragment of a corner portion of the stove shown in Fig. 1 illustrating the manner in which certain decorative elements of the stove are attached in place thereon.

Fig. 3 is a section on line 3—3 of Fig. 2, 45 portions of certain decorative elements 50 shown therein being shown in section to illus-

trate the manner in which said elements are secured in place.

Fig. 4 is a section on line 4—4 of Fig. 2.

Fig. 5 is a perspective of one of the corner pieces which are associated with the decorative elements of a stove made in accordance with the invention.

In the drawing which illustrates one embodiment of the invention A designates a stove of the range type, which comprises supporting legs B on which a front wall 1, a rear wall 2, and side walls 3 and 4 are supported. The stove is also provided with the usual hinged oven door C provided with elements D for maintaining same in a horizontal position and said stove is provided with the usual interior construction which goes with stoves of this type, but as said interior construction does not form a part of the present invention same has not been illustrated.

Referring now to Fig. 1 of the drawing it will be noted that at a point removed inwardly a slight distance from each side marginal edge of each side wall of the stove A the material of which the side wall is formed is offset to provide a wall 5 which is arranged at an approximate right angle to the main body portion of the side wall and extends from the top edge of the side wall to the bottom edge thereof. The material of which the side wall is formed is also bent at each side edge thereof at an approximate right angle with respect to the wall 5 to provide a vertically disposed wall 6 which extends from the top to the bottom of the wall. Each side wall is also shaped at each side edge thereof so that same is provided with a marginal wall 7 arranged parallel with and spaced from the associated wall 5 and a wall 8 parallel with and spaced from the associated wall 6. The walls 7 and 8 like the walls 5 and 6 extend from the top edge to the bottom edge of the side wall with which they are associated and as shown clearly in Figs. 1 and 3 the associated walls, 5, 6, 7, and 8 provide each side wall with approximately L-shaped guideways at the opposite side edges thereof.

As will be observed by referring to Figs. 1 and 3 the outer face of each of the walls 8 is spaced inwardly from the outer face of the main body portion of 100

the associated side wall, which arrangement is for a purpose to be hereinafter set forth.

Considering now the front wall 1 and the rear wall 2 it will be noted that at the opposite side edges of each of said walls the material of which the wall is formed is bent at an approximate right angle to provide vertically arranged walls 9 which in the case of the front wall are projected rearwardly and in the case of the rear wall are projected forwardly of the stove A, said walls 9 being extended from the top to the bottom edges of the associated front and rear walls. In like manner the material of which the front and rear walls 1 and 2 are formed at the inner edges of the walls 9 is bent to provide inwardly projected, vertically arranged walls 10 which are approximately parallel with the main body portions of said walls and said material is also bent to provide outwardly projected, vertically arranged walls 11 which are located at the inner ends of the walls 10 and are approximately parallel with the walls 9.

It will be observed that the arrangement of the walls 9, 10, and 11, at the opposite side edge of each of the front and rear walls 1 and 2 is such that an approximately L-shaped guideway is provided adjacent to each side edge of each of said walls and like the guideways formed at the opposite side edges of the side walls 3 and 4, the guideways at the opposite side edges of the front and rear walls extend from the top to the bottom edges of said walls.

In assembling a stove made in accordance with this invention the front and rear walls 1 and 2 or the side walls 3 and 4 are maintained in their proper vertical positions, it being assumed, for instance here that the front and rear walls are so maintained. In this event the side walls will be elevated and the walls 7 and 8 thereof will be introduced into the L-shaped guideways formed at the side edges of the front and rear walls respectively, while the walls 10 and 11 at the side edges of the front and rear walls pass into the L-shaped guideways at the side edges of the side walls 3 and 4. The side walls will then be moved downwardly with respect to the front and rear walls so that the walls 7 and 8 thereof will pass longitudinally through the guideways provided at the side edges of the front and rear walls while the associated walls 10 and 11 of the front and rear walls are passing longitudinally through the L-shaped guideways at the side edges of the side walls and because of the arrangement of the walls and guideways in association with the respective parts interlocking joints are provided by means of which the parts are securely fastened together. Due to the fact that the walls 8 are offset inwardly with respect to the main body portions of the side walls 3 and 4 the outer faces of the main body portions of the side walls 3 and 4 whereby the smooth ap-

pearance of the sides of the stove will be maintained.

Arranged at the lower edges of the front, side and rear walls of the stove A is a plurality of members 13 there being one of said members at the bottom edge of each of the walls mentioned. Each of the members 13 comprises a base portion 13^a and a pair of flange portions 13^b at the upper and lower edge of the base portion. The base portion 13^a of each of the members 13 contacts with the stove wall with which the member is associated and rivets, or other suitable fastening devices 14, are extended through said base portions and through the associated wall to secure said member to said wall, the flange portions 13^b being spaced apart from the associated wall of the stove as shown in Fig. 4. 15 designates a plurality of decorative elements one of which is associated with each member 13, said elements in cross-section comprising each a face portion 15^a and inwardly turned flange portions 15^b (Fig. 4).

To cause the decorative elements 15 to be supported by the members 13, said elements 15 being aligned with the associated member 13 so that the flange portions 15^b thereof may be introduced between the flange portions 13^b of the members 13 and the face of the associated wall of the stove. With the parts so arranged the decorative elements are moved longitudinally of the associated members 13 to cause said members 13 to support the decorative elements 15.

As indicated by the dotted lines designated by the reference character E, in Figs. 2 and 3 the members 13 terminate some distance short of the corners of the stove A and as will be apparent from the views mentioned, the decorative elements 15 are longer than the associated members 13 so that the opposite end portions of the elements 15 extend beyond the corresponding ends of the associated members 13.

16 designates corner pieces each of which comprises a rectangular body portion provided with projections 17 at the outer ends thereof (Fig. 5). One of the corner pieces 16 is arranged at each corner of the stove with the legs of the rectangular body portion thereof in alignment with the decorative elements 15 supported by walls forming a rectangular corner of said stove, and with the projections 17 of the corner piece extended into the space between the inner faces of the face portions 15^a of the elements 15 and the adjacent faces of the walls of the stove and with the top and bottom edges of said projections contacting with the inner edges of the flange portions 15 of said decorative elements.

In view of this arrangement it is plain a continuous decorative element which may be nickel-plated or otherwise treated, is provided about the lower edge of the stove and

in view of the arrangement of the parts making up this decorative element no fastening devices will be visible at the outer face of the stove, the corner pieces 16 being supported by the elements 15 and said elements 15 being supported by the members 13 the fastening devices of which are hidden by the elements 15. Also because the projections 17 are offset rearwardly from the front faces of the legs 10 of the rectangular body portion of the corner pieces 16 as shown in Fig. 3 the front face of the decorative band formed about the stove by the elements 15 and the corner pieces 16 is smooth and unbroken.

Having thus described my invention, what I claim as new and desire to secure by Letters Patent of the United States is:

1. A stove comprising a supporting member fixed to a wall thereof and having marginal flange portions spaced outwardly from the wall to which said member is fixed, and a corner piece provided with a projection extended behind a portion of said decorative element, whereby said corner piece is supported.

2. A stove comprising a pair of supporting members fixed to walls of a stove which are arranged at an approximate right angle to each other, said supporting members being provided each with flange portions spaced from the stove wall with which the member is associated, decorative elements embracing said supporting members and having flange portions slidably engageable with the flange portions on said supporting members whereby said decorative elements are supported by said supporting members, and a corner piece having projections engageable behind portions of said decorative elements whereby said corner piece is supported.

In testimony that I claim the foregoing I hereunto affix my signature.

GUILFORD S. MORLEY.
